UNITED STATES PATENT OFFICE.

EUGENE D. ARWINE, OF SAN JOSE, CALIFORNIA.

THUMB-KNIFE.

1,000,226.

Specification of Letters Patent.

Patented Aug. 8, 1911.

Application filed July 22, 1910. Serial No. 573,338.

To all whom it may concern:

Be it known that I, EUGENE D. ARWINE, residing at San Jose, in the county of Santa Clara and State of California, have invented a new and Improved Thumb-Knife, of which the following is a specification.

My invention relates to improvements in that class of devices for picking fruit and certain of the garden vegetables, that are especially designed for being worn on the thumb or fingers of the hand and it has for its object to provide a device of the character stated of a simple and inexpensive construction, which while embodying the desired feature of rigidity, is so shaped that it does not interfere with the normal movements of the first joint of the thumb, or in any manner interfere with such member during the operation of plucking fruits or vegetables.

With other objects in view that will hereinafter appear, my invention comprehends a metallic thimble having a severing member at the outer end, and a flexible portion for extending back over the thumb joint provided with means for drawing the inner end of the said flexible member tightly onto the thumb.

My invention in its more subordinate features, embodies a thimble knife having the peculiar construction and combination of parts, hereinafter fully described, specifically pointed out in the appended claim and illustrated in the accompanying drawings, in which:

Figure 1, is a perspective view of my device, and illustrates the manner in which it is used for plucking grapes. Fig. 2, is a similar view and shows the manner in which the thimble can be directed for severing the stems of apples, pears and the like. Fig. 3, is a longitudinal section of the device. Fig. 4, is a perspective view of the device looking at the under side thereof. Fig. 5, is a view of the blank from which the thimble is bent up. Fig. 6, is a plan view of a slightly modified arrangement of the cutting end. Fig. 7, is a transverse section on the line 7—7 on Fig. 3. Fig. 8, is a similar view on the line 8—8, and Fig. 9, is a view of a slightly modified form of the flexible end of the device.

In the practical application of my invention and in its preferred shape, the thimble is bent up from a single piece of metal having the blank form shown in Fig. 5, by ref-

erence to which it will be observed the blank *a* is of substantially segmental shape, the outer or small end *b* being cut square across in a line parallel with the longest arc of the blank indicated by the dotted line *x* and the said end *b* is cut out to form V shaped notches *c*—*c* that produce the angle extensions *d*—*d* and a central blade like member *e*. About midway their length, the opposite angle edges of the blank have concavities *f*, and at the inner or larger end of the blank is provided with a number of short slots *g* the purpose of which will presently appear.

The blank *a*, when bent up forms a thimble like sheath 1, and in bending the blank to shape the angle extensions are turned inwardly to form a closure 10 for the outer end of thimble, at a point back of the cutter or severing knife *e*, the latter extending in the plane of the back or upper face of the thimble. The thimble 1 as will be clearly understood from the drawings in practice is of a length and size to snugly slip onto the outer end of the thumb and with its inner end positioned forward of the first thumb joint so that the natural movement of the said joint is not interfered with.

Heretofore in devices of this kind, means like spring metal clamp, formed with or attached to the thimble have been utilized for securing the thimble on the thumb or finger to securely hold it during the operation of picking the fruits or vegetables. This form of holding means, from practical experience, I have found as objectionable, especially since they restrict the use of the thumb and particularly interfere with the joint movement thereof. In my invention, special provision is made for conveniently securing the thimble on the thumb and yet leave the thumb unrestricted for its natural movements. For this purpose I use a fabric sheath or stall 2 that extends down to near the cutting end of the thimble and is of such length that it continues far back over the outer joint of the thumb and the said sheath 2 has its outer end provided with a draw string 3, for tightly drawing the said outer end of the sheath onto the thumb, as will be clearly understood from the drawing, it being also clear that an elastic hemmed in the outer end of the sheath, see Fig. 9, will accomplish the same result. The cloth sheath 2 is made fast to the insides of the metal thimble by the stitching 4 that

passes through the several slots in the curved end of the thimble.

By reason of the peculiar construction of my invention, as described and shown, the picker can readily use the thimble for severing different kinds of fruit, and can easily adjust the angle or direction of thrust of the thimble knife to suit the character of the stem to be severed; for example, when 10 picking a bunch of grapes (see Fig. 1) the thimble may be extended in an almost straight line, while in gathering apples, oranges and similar fruit, the thimble can be readily shifted to bring the blade at the 15 bottom to cut close to fruit by bending the thumb joint nearly at right angles to the base of the thumb. Again by reason of forming the knife edge and the thimble as 20 stated, the knife is not in the picker's way while handling the fruit (as in conveying the fruit from the tree or vine to the storing box or receptacle).

While on the score of economy of manufacture, I prefer to make the knife edge an 25 integral part of the thimble, it may be a separate member secured to the thimble in any approved manner, see Fig. 6.

By forming the sides of the blank from 30 which the thimble is bent up with concaved recesses, a round hole 5 is provided in the bottom of the thimble that is covered on the inside by the cloth sheath. This hole comes over the ball or palm of the thumb, and 35 thereby still further renders the thimble less cumbersome in its use as the ball of the

thumb can be utilized for gripping branches, stems, etc.

While I have especially described my invention as designed for cutting fruit and vegetable stems, it is obvious it may be 40 generally utilized for cutting twine when wrapping up merchandise and parcels.

Having thus described my invention, what I desire to secure and claim by Letters Patent is:

A picking device of the character stated, comprising a sheet metal blank bent to form a thimble to inclose the end of a finger, one end of said thimble having a forwardly projecting cutter and the other end of said 50 thimble being open and provided with an annular series of perforations, a fabric finger stall to completely cover the end of a finger and projecting into said thimble, stitching passing through said annular series 55 of perforations and through said fabric stall to secure said thimble and stall together adjacent to the open end of said thimble, said stall having its open end projected beyond the open end of said thimble to pass the 60 first joint of a finger, said finger stall having its open end bent back upon itself to form an annular pocket, and means in said annular pocket for drawing said open end of said fabric stall into tight contact with the 65 finger of the user.

EUGENE D. ARWINE.
